UNITED STATES PATENT OFFICE

ALBERT W. HULL, OF SCHENECTADY, NEW YORK, ASSIGNOR TO GENERAL ELECTRIC COMPANY, A CORPORATION OF NEW YORK

SPACE DISCHARGE DEVICE

Application filed August 31, 1927. Serial No. 216,679.

The present invention relates to space discharge devices and more particularly to an arrangement for controlling a three-electrode space discharge device by means of 5 light impulses.

It is one of the objects of the present invention to provide an improved three-electrode space discharge device in which no leading-in wire is brought through the glass container 10 from the control member of the discharge device.

The novel features which I believe to be characteristic of my invention are set forth with particularity in the appended claims.

15 The invention itself, however, will best be understood from reference to the following specification when considered in connection with the accompanying drawings in which Fig. 1 represents a view partly broken away 20 of a three-element space discharge device which embodies the features of my invention; Fig. 2 shows diagrammatically one application of the discharge device shown in Fig. 1, while Figs. 3 and 4 show modified 25 forms of the invention disclosed in Fig. 1.

Referring more particularly to the drawings, I have indicated at 10 an evacuated receptacle having the usual reentrant portion 11 and stem portion 12 through which leading-in wires 13, 14, 15 and 16 extend. Wires 30 14 and 15 are connected to a filamentary electrode 17 while wire 16 is connected to a grid form of electrode 18 which, in the present instance, is the anode. The plate member 19 which constitutes the control member of the 35 discharge device is supported by a pair of electrodes 20 and 21 which cooperate with a light sensitive, cylindrical electrode 22. Electrode 22 is connected to the leading-in 40 wire 13. Electrodes 20 and 21 are supported by a pair of insulating beads 23 and 24 of refractory material, such as quartz, alumina or other suitable substance of high insulating 45 quality. These beads are mounted on the ends of short wire stems 25 and 26 which are fused into the end of the glass stem 12.

A light sensitive coating is obtained on the electrode 22, as well as on the electrode 19, by vaporizing a small amount of caesium 50 or other alkali metal within the container 10,

or by suitably treating the respective surfaces.

With the construction indicated it will be apparent that the potential of the plate electrode 19 is controlled by the electrodes 20 and 21 which are electrically insulated from the exterior of the receptacle 10, and that no lead for the control electrode 19 extends through the stem 12. In this manner any electrical leakage along the surface of the glass stem 55 or reentrant portion 11 is prevented.

Although beads of quartz or alumina, such as 23 and 24, provide excellent electrical insulation under ordinary vacuum conditions, it may be found advisable when employing an 60 excess of free caesium in the tube, to surround the beads with coils 27 and 28 which are included in the filament circuit, as indicated in Fig. 3. The heat produced by the current flowing through these coils heats the 65 beads sufficiently to prevent any condensation of caesium onto the beads thereby to preclude electrical leakage. Or if desired cup-shaped shields 28' may be mounted over the insulating beads as indicated in Fig. 1. 70

In the arrangements shown in Fig. 4 the upper part 29 of the envelope or container comprises a light sensitive cell which is separated from the lower three-element discharge device or valve 30 by a glass partition 31. In 75 this figure the control electrode of the three-element discharge device is the usual grid 18' and it is connected to the cathode element 32 of the light sensitive cell 29 by wires 33 and 34, while the anode member 19' of the discharge device is connected to the electrode 35. Operation of this form of discharge device is similar to the operation of the devices shown in Figs. 1 and 3. The separation of the container into two parts, however, permits the application of light sensitive material solely to the elements comprising the light sensitive or photo-electric cell. The filament of the amplifier may therefore be of any type, for example a thorium coated tungsten 80 filament, without danger of excess photo-electric action of its light upon the grid. 85

One application of my improved discharge device is indicated in Fig. 2 which discloses 90 diagrammatically a circuit arrangement for 100

automatically controlling the temperature of an electric furnace by means of light given off by the furnace. In the arrangement shown the filament 17 is supplied from a suitable source of energy 36 through a ballast lamp 37 which serves to keep the temperature of the filament substantially constant. Light from a furnace to be controlled is directed on to the light sensitive cylindrical electrode 22 through an opening 38 therein, causing this electrode to give up electrons to the wires or electrodes 20 and 21 which are connected to the plate or control electrode 19. This action tends to make the plate 19 less positive. At the same time, however, light from the filamentary electrode 17 falls upon the control member 19, which is coated with caesium and causes it to lose electrons and become more positive and thereby normally establishing a balanced photo-electric effect between the light from the filament 17 and the light directed onto the electrode 22. If the light from the furnace is weak the plate or control electrode 19 will obviously be positive and current will flow in the anode or output circuit of the discharge device. A resistor 39 is included in the output circuit of the discharge device and the drop across this resistor will control the potential supplied to the grid or control element 40 of a second discharge device 41. When the full output current of the first discharge device is flowing the potential applied to the grid 40 will be so negative that the discharge device 41 will not operate. No current flows in its output circuit under such circumstances and relay 42 included in the output circuit of tube 41 remains deenergized. If the temperature of the furnace to be controlled is raised slightly so that the light from it exceeds a predetermined amount, the control electrode 19 will become negative thus cutting off the flow of anode current, allowing the grids 40 of the discharge device 41 to assume cathode potential, and permitting current to flow in the output circuit of tube 41, thereby energizing relay 42 and in that manner adjusting the resistance of the furnace.

In the arrangement shown in Fig. 4 it will be apparent that when the filament is lighted, electrons are supplied to the grid tending to make it negative and that light supplied to the cylindrical electrode removes electrons from the grid thereby tending to make it positive and in this manner establishing a balanced effect between the light from the filament and light directed onto the light sensitive cell. The action in the device shown in this figure is similar to the action which takes place in the device shown in Figs. 1 and 3, but the arrangement disclosed in Fig. 4 requires one less leading-in wire than the devices shown in Figs. 1 and 3 and avoids the use of alumina or quartz insulating beads.

What I claim as new and desire to secure by Letters Patent of the United States, is:—

1. In combination, a photo-electric device comprising a receptacle having a reentrant portion provided with a stem, a cathode, anode and control electrode mounted in said device, said control electrode being coated with a highly reactive light-sensitive material, leading-in wires extending through said reentrant portion and stem and connected to the anode and cathode and means for supporting the control electrode on said stem, said means comprising an insulating bead of refractory material and means for preventing the collection of excess light-sensitive material on said bead. 70 75 80

2. A space discharge device comprising an anode, a filamentary electrode and a control electrode, said control electrode being provided with a light sensitive surface, means for normally balancing the photo-electric effect produced by the action of the lighted filament on said control electrode, said means comprising another light sensitive electrode, and a second electrode cooperating with said light sensitive electrode and connected to the control electrode. 85 90

3. A space discharge device comprising an anode, a filamentary electrode and a control electrode, said control electrode being provided with a light sensitive surface, means for normally balancing the photo-electric effect produced by the action of the lighted filament on said control electrode, said means comprising another light sensitive electrode 100 and a second electrode cooperating with said light sensitive electrode and connected to the control electrode but insulated from the outside of said discharge device. 95

4. In combination, a photo-electric device 105 comprising a receptacle having a reentrant portion provided with a stem, a cathode, anode and control electrode mounted in said device, said control electrode being coated with a highly reactive light-sensitive material, leading-in wires extending through said stem and connected to the anode and cathode, means for supporting the control electrode on said stem and means for preventing electrical leakage about the supporting means. 110 115

In witness whereof I have hereunto set my hand this 29th day of August, 1927.

ALBERT W. HULL.
